US00D876693S

(12) **United States Design Patent** (10) Patent No.: **US D876,693 S**
Mishan (45) Date of Patent: **** Feb. 25, 2020**

(54) **FLASHLIGHT BATON WITH CRENULATE SLIDING BEZEL**

(71) Applicant: **E. MISHAN & SONS, INC.**, New York, NY (US)

(72) Inventor: **Steven Mishan**, New York, NY (US)

(73) Assignee: **E. MISHAN & SONS, INC.**, New York, NY (US)

(**) Term: **15 Years**

(21) Appl. No.: **29/612,757**

(22) Filed: **Aug. 3, 2017**

(51) LOC (12) Cl. **26-02**

(52) U.S. Cl.

USPC **D26/38; D22/117**

(58) **Field of Classification Search**

USPC D26/37-51; D22/117; D21/725

(57) **CLAIM**

The ornamental design for a flashlight baton with crenulate sliding bezel, as shown and described.

DESCRIPTION

FIG. 1 is a left, top, perspective view of a flashlight baton with crenulate sliding bezel showing my design therefor; FIG. 2 is a front view of the flashlight baton with crenulate sliding bezel of FIG. 1; FIG. 3 is a rear view of the flashlight baton with crenulate sliding bezel of FIG. 1; FIG. 4 is a right side view of the flashlight baton with crenulate sliding bezel of FIG. 1; FIG. 5 is a left side view of the flashlight baton with crenulate sliding bezel of FIG. 1; FIG. 6 is a top view of the flashlight baton with crenulate sliding bezel of FIG. 1; FIG. 7 is a bottom view of the flashlight baton with crenulate sliding bezel of FIG. 1; FIG. 8 is a left, top, perspective view of the flashlight baton with crenulate sliding bezel of FIG. 1 with the crenulate sliding bezel in a partially forward position; FIG. 9 is a front view of the flashlight baton with crenulate sliding bezel of FIG. 8; FIG. 10 is a rear view of the flashlight baton with crenulate sliding bezel of FIG. 8; FIG. 11 is a right view of the flashlight baton with crenulate sliding bezel of FIG. 8; FIG. 12 is a left view of the flashlight baton with crenulate sliding bezel of FIG. 8; FIG. 13 is a top view of the flashlight baton with crenulate sliding bezel of FIG. 8; FIG. 14 is a bottom view of the flashlight baton with crenulate sliding bezel of FIG. 8; FIG. 15 is a left, top, perspective view of the flashlight baton with crenulate sliding bezel of FIG. 1 with the crenulate sliding bezel in a fully forward position; FIG. 16 is a front view of the flashlight baton with crenulate sliding bezel of FIG. 15; FIG. 17 is a rear view of the flashlight baton with crenulate sliding bezel of FIG. 15; FIG. 18 is a right view of the flashlight baton with crenulate sliding bezel of FIG. 15; FIG. 19 is a left view of the flashlight baton with crenulate sliding bezel of FIG. 15; FIG. 20 is a top view of the flashlight baton with crenulate sliding bezel of FIG. 15; and, FIG. 21 is a bottom view of the flashlight baton with crenulate sliding bezel of FIG. 15. The broken lines show portion of the article which form no part of the claimed design.
